By Wm. W. Clark & Carpenter
Atty's

UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

TALCUM-POWDER CAN.

Application filed February 11, 1922. Serial No. 525,907.

This invention relates in general to talcum powder cans, and has more particular reference to the provision of a cap closure for such a can provided with a gasket 5 cured in place in peculiarly effective manner.

A principal object of the invention is the provision of an improved method and construction of a talcum powder can top which provides a tight closure preventing the escape of powder when the parts are in closed relationship.

Numerous other objects and advantages of the invention will be apparent as it is better understood from the following description, 15 which, taken in connection with the accompanying drawings, discloses a preferred embodiment thereof.

Referring to the drawings,

Figure 1 is a vertical section through the 20 cap and container top;

Fig. 2 is a plan view of the container;

Fig. 3 is a bottom plan view of the cap; and

Fig. 4 is a section taken transversely there- 25 through.

For the purpose of illustration, I have shown on the drawings a container body 11 of generally oval formation, provided with an inclined top portion 12 to which is suitably secured at 13 a neck 14 having a perforated top part 15. A cap 16, which may be of any desired peripheral configuration, is rotatably fitted upon the neck 14, the top part of said cap being perforated to correspond to the perforations of the top part 30 15 when in registration therewith.

A gasket 17 is seated in the top of the cap and serves to prevent leakage of the powder when the respective perforations of the container top part and cap are out of registration, or in other words, in closed position. 40 It will be noted that the cap is provided with a central upwardly extending recess 18 which, in the present instance, is of hexagonal form, though it will be understood that the exact form may be varied, being preferably, however, of non-circular or irregular outline. The gasket is formed to shape corresponding to the shape of the recess 45 18 in the cap and fits closely against the top part 15 seated in said recess.

In order to secure the gasket in place without special holding means, I place it upon the metal blank, from which the cap is to be

formed, prior to the formative operation 55 thereon, and the forming dies serve to shape the gasket and metal cap together in such manner that said gasket is securely held in the recess 18 in the finished cap. The gasket flange 19 extends beyond said recess and 60 preferably into close contact with the vertical wall 21 of the cap and is thus held against removal by said wall and by the hexagonal walls 22 of the recess. I have found that when assembled in this manner 65 the gasket remains securely held in place under conditions of service, and the economy of manufacture in accordance with the method described will be obvious.

It is thought that the invention and many 70 of its attendant advantages will be understood from the foregoing description, and it will be apparent that various changes may be made in the form, construction and arrangement of the parts without departing from 75 the spirit and scope of the invention or sacrificing all of its material advantages, the form hereinbefore described being merely a preferred embodiment thereof.

I claim:

1. A talcum powder can, comprising a body having a perforated top part, and a perforated cap rotatably fitting said top part, said cap having a polygonal recess and being provided with a gasket seated in said 85 recess and held in place by the walls thereof.

2. A talcum powder can, comprising a body having a perforated top part, and a perforated cap rotatably fitting said top part, said cap having a polygonal recess and being provided with a gasket seated in said recess and held in place by the walls thereof, and said top part having a central portion fitting in said gasket lined recess. 90

3. A talcum powder can, comprising a body having a perforated top part, and a perforated cap rotatably fitting said top part, said cap having a polygonal recess and being provided with a gasket seated in said recess and held in place by the walls thereof, 95 said gasket extending beyond said recess and having its edges in engagement with the vertical wall of the cap. 100

4. A talcum powder can, comprising a body, a top having a raised central perforated portion forming an upwardly extending projection, and a cap having a raised and perforated central portion forming an 105

upwardly extending recess to receive said projection of the top and being provided with a gasket formed therewith and in accordance with the contour thereof, said 5 gasket having a flange extending beyond said raised central portions and into contact with the vertical wall of the cap.

5. A talcum powder can, comprising a body, perforated top part and a cap rotatably fitting upon said top part and provided with an interior non-circular gasket-holding top part, and a gasket secured in 10 place by being drawn with the metal of the

cap to the finished non-circular form of the interior of the top of the cap. 15

6. The combination of a cap having a non-circular recess formed on the underside of its top, a gasket non-rotatably fitted in said recess; said top and gasket being correspondingly perforated, and a neck on which said cap is rotatably fitted and having a top fitting against said gasket and perforated to correspond with the perforations of said cap and gasket. 20

JOHN M. HOTHERSALL.
